ATTACHMENT FOR PRINTING PRESSES

George B. Sammons, Washington, D. C.

Application January 28, 1941, Serial No. 376,400

12 Claims. (Cl. 101—416)

The present invention relates to attachments for printing presses and refers particularly to a flame guard for the outfeed end of a printing press.

In the operation of printing presses it has been found that the printed sheets become charged with static electricity. This has the effect of making the sheets stick or adhere to each other after they have been deposited in the discharge hopper or receptacle.

To eliminate this objectionable feature, it has been customary to place a flame producing means in the path of the sheets, between the end of the sheet feeding means and the discharge hopper. The flame tends to discharge or eliminate the charge of static electricity from the sheets and thus prevents them from sticking together after they are deposited in the hopper.

In actual practice, I have ascertained that in many instances, a sheet of paper will accidentally come to rest over the flame or will bounce back from the hopper after it has passed over the flame. In either instance the flame will immediately ignite the sheet, making it necessary to stop the press until the burning sheet can be removed. This greatly impairs the efficiency of the press and causes considerable loss of time as well as possible injury to the press.

The present invention is designed to eliminate this objectionable feature by providing means for momentarily shielding the flame after a sheet has passed over the flame, and during the interval between the discharge of one sheet into the hopper and the presentation of the next sheet to the flame. Thus, if for any reason a sheet should accidentally come to rest over the flame instead of being deposited in the hopper, or if it should accidentally bounce back from the hopper, the shielding means prevents burning of the paper or at least prevents any sustained or uninterrupted action of the flame upon the sheet, so that the attendant will have an opportunity to remove the sheet before it becomes ignited.

In association with the flame shielding means, a gas control valve is provided and this valve is connected with the flame shielding means whereby the flame is diminished during the operation of the shield; that is, there is a co-operation of these elements to simultaneously diminish the flame and shield it momentarily from the sheets after each sheet has passed over the flame.

In addition to the flame shielding means I have also provided means, preferably located

between the flame producing means and the hopper for preventing accidental return of the sheets over the flame after they have been deposited in the hopper.

With the foregoing and other objects in view the invention will now be more fully described, reference being had to the accompanying drawing, in which:

Figure 1 is a side elevation partly in section of the present invention,

Figure 2 is an enlarged perspective view thereof, and

Figure 3 is a modification of the guard.

Referring now to the drawing, the numeral 10 designates the outfeed or discharge end of a printing press. This may be of any desired construction and in the drawing is illustrated as comprising a pair of upper and lower conveyors 11 and 12, respectively. The discharge end of the upper conveyor travels around a roller 13, while the lower conveyor passes over rollers 14, 15 and 16, respectively.

The conveyors and rollers are mounted on a longitudinally extending frame 17 consisting in part of spaced side frame members or bars 18 and 19, respectively. Within the frame 17 is also mounted a sheet receiving hopper or repository 20 having a vertically extending wall 21 adjacent to but spaced a slight distance from the end of the conveyors 11 and 12. This hopper is provided with a movable bottom wall 22 which is automatically lowered to accommodate the sheets as they are deposited in the hopper from the outfeed end of the printing press.

Sufficient space is provided between the ends of the conveyors 11 and 12 and the wall 21 of the hopper for the reception of a flame producing means. In the present instance this comprises a perforated pipe 23 extending transversely of the frame so as to produce a flame extending across the path of the sheets as they are discharged from the conveyors 11 and 12 into the hopper 20. As previously explained, the purpose of the flame is to eliminate or discharge the charges of static electricity in the sheets so as to prevent them from sticking together after they have been deposited in the hopper 20.

The perforated pipe 23 may be mounted in any desired manner such as by means of a plurality of spaced blocks 24 secured to the upper end of the wall 21 by means of fastening elements 25. As shown in Figure 1, these blocks are notched to partially receive the pipe. One end of the pipe is closed, while the other end connects with a supply line 26, through which gas

or other illuminating medium is supplied to the pipe 23. In the event that a sheet accidentally comes to rest over the pipe during the operation of the press, or if a sheet should bounce back out of the hopper to a position over the flame, the flame issuing from the pipe 23 would ignite the paper and possibly cause damage to the machine and make it necessary to temporarily stop operation of the press. The present invention is designed to eliminate this objectionable feature so that if a sheet should accidentally come to rest over the pipe 23, the operator or attendant will have ample opportunity to remove the sheet before it is ignited by the flame.

This mechanism comprises means for momentarily shielding the flame directly after a sheet has been deposited in the hopper and before the next sheet is discharged from the conveyors 11 and 12. One embodiment of this shielding means is illustrated in Figures 1 and 2 and comprises a curved plate 26 fixed to a shaft 27 which extends transversely of the frame and has its opposite ends journalled in a pair of upstanding posts 28 and 29, respectively, mounted on the side frame members or bars 18 and 19. As will be observed, the shaft 27 extends in close proximity to the pipe 23 so that upon rotation thereof, the plate or shield 26 may be moved directly over the perforations 30 of the pipe and thus shield the flame from the sheets passing from the conveyors 11 and 12 to the hopper.

Any desired means may be employed to operate the shield 26 in timed relation with the feeding of the sheets so that the shield will be moved over the pipe directly after a sheet has been deposited in the hopper. In the present instance, I utilize part of the mechanism which actuates the joggers. Since this jogger mechanism does not form part of the present invention, only that portion which directly concerns the shielding mechanism 26 has been illustrated. This comprises a cross shaft 31 journalled in the posts 28 and 29 above the shaft 27. At each end of the shaft 31 inside its respective post is located a sleeve 32 which is adjustably secured to the shaft by means of a set screw 33. Each sleeve 32 is provided with an integral and downwardly extending arm 34, which, in turn, is adjustably connected to a flat plate 35 by means of fastening elements 36. The lower end of each plate 35 is formed with a plurality of teeth which mesh with cooperating teeth upon an arm 37 secured to a sleeve 38 adjustably mounted adjacent one end of the shaft 27 by a set screw 39.

During operation of the jogger mechanism the arm 40 connecting one end of the shaft 31 is oscillated and this motion is transmitted through the shaft 31 to the arms 34 and plates 35. The teeth of the plates 35 meshing with the teeth of the arms 37 oscillate these arms and transmit an oscillating motion through the shaft 27 to the shield 26. It is to be understood that the motion of the jogger mechanism is synchronized with the sheet feeding mechanism, so that the shield 26 will move over the flame issuing from the pipe 23, immediately after the end of a sheet 41 has passed over the pipe and into the hopper 20.

In addition to the shielding means I also provide means for diminishing flow of gas to the pipe as the shield 26 is moved over the perforations 30. This means is also actuated by the shaft 31 and comprises a valve 42 of any desired construction inserted in the supply line 26 adjacent the pipe 23. This valve has a reciprocating

stem 43 which is adjustably connected to a rod 44 pivoted to one end of an arm 45, the other end of this arm being fixed to the shaft 31. It will be apparent that as the shaft 31 is actuated to oscillate the plates 35 and transmit an oscillating motion to the shield 26, it also oscillates the arm 45, reciprocating the valve stem 43 and intermittently decreasing the flow of gas to the pipe 23. It is to be understood that the operation of the valve does not entirely cut off the flow of gas to the pipe but merely decreases it to such an extent that the flame is greatly diminished at the time that the shield 26 is positioned over the perforations 30.

With the present construction I have provided means for simultaneously diminishing the flame and also shielding the same at predetermined times during the operation of the press. This mechanism prevents a steady sustained flame which would tend to immediately ignite a sheet of paper or other inflammable material if it should accidentally come to rest over the pipe 23 instead of being deposited in the hopper 20. While the pipe is merely shielded momentarily, or intermittently, I have found that the construction is such as to prevent immediate ignition or burning of a sheet that has accidentally come to rest over the pipe. Thus, the operator or attendant will have adequate time within which to move the sheet before it burns and thus prevent injury to the machine.

As an additional means for preventing the sheets from actually coming to rest over the pipe 23, I have provided a guard member associated with the hopper mechanism for preventing the sheets from bouncing back from the hopper to a position over the pipe after they have been discharged from the conveyors 11 and 12 into the hopper. This guard means comprises a transversely extending plate 46 which is clamped between the top of the wall 21 and the plugs 24 by the fastening elements 25. (See Figure 1.) The upper end of the plate 46 is bent rearwardly and downwardly to form an overhanging lip 47 which projects within the hopper sufficiently to engage the edges of the sheets and thus prevent these sheets from bouncing back out of the hopper and over the pipe 23. The present invention not only provides means for diminishing and shielding the flame from the sheets at certain intervals, but also employs structure which will prevent accidental return of the sheets from the hopper to a position over the pipe.

To facilitate the passage of the sheets over the guard and to prevent smudging of the sheets in the event they are printed on both sides, a plurality of star wheels 48 are provided which project through curved slots 49 in the top of the guard. These star wheels are fixed to a shaft 50 suitably journalled between the frame members 18 and 19.

Figure 3 discloses a modified form of the guard 46 in which a horizontal shoulder 51 is positioned between the vertical wall 52 and the curved lip 53. This is for the purpose of extending the lip further into the hopper without increasing its size. This arrangement may be desirable in some instances where the sheets are of less size than the width of the hopper.

It is understood that the invention is not limited to the details of construction shown in the drawing and that the phraseology employed in the specification is for the purpose of description and not of limitation. Thus the flame shielding means and the control valve may be operated

from any source independently of the press operating means, and the shield supporting shaft may be journaled in the side frame members or other support if desired.

I claim:

1. In a device of the character described, a sheet repository, means for feeding electrically charged sheets to said sheet repository, flame producing means fixedly mounted between the discharge end of the sheet feeding means and the sheet repository for directing a flame across the path of the sheets to discharge the electric charge therefrom before they are deposited in the repository, and means for momentarily rendering the flame producing means inoperative to provide an effective flame in the path of the sheets after a sheet has passed over the flame, to thereby prevent burning of a sheet which may accidentally come to rest over the flame.

2. In a device of the character described, means for feeding electrically charged sheets to a sheet repository, a sheet repository located at the discharge end of the sheet feeding means to receive the sheets therefrom, flame producing means including a perforated pipe fixedly positioned between the sheet feeding means and the repository transversely of the path of the sheets, and means for momentarily rendering the flame issuing from the pipe ineffective after a sheet has passed over the flame, to thereby prevent burning of a sheet which may accidentally come to rest over the flame.

3. In a device of the character described, means for feeding electrically charged sheets to a sheet repository, flame producing means located at the discharge end of the sheet feeding means for directing a flame across the path of the sheets to discharge the electric charge therefrom before they are deposited in the repository, a flame shield movably mounted adjacent the flame producing means, and means for operating the flame shield to momentarily shield the flame from the path of the sheets after a sheet has passed over the flame, to thereby prevent burning of a sheet which may accidentally come to rest over the flame.

4. In a device of the character described, means for feeding electrically charged sheets to a sheet repository, flame producing means located at the discharge end of the sheet feeding means for directing a flame across the path of the sheets to discharge the electric charge therefrom before they are deposited in the repository, a flame shield movably mounted adjacent the flame producing means, and means operated in timed relation with the sheet feeding means for actuating the shield to momentarily shield the flame from the path of the sheets after a sheet has passed over the flame, to thereby prevent burning of a sheet which may accidentally come to rest over the flame.

5. In a device of the character described, means for feeding electrically charged sheets to a sheet repository, a sheet repository located at the discharge end of the sheet feeding means to receive the sheets therefrom, flame producing means including a perforated pipe positioned between the sheet feeding means and the repository transversely of the path of the sheets, a flame shield movably mounted adjacent the pipe and adapted to be moved over the pipe to shield the sheets from the flame, and means for operating the flame shield to momentarily shield the flame from the path of the sheets after a sheet has passed over the flame, to thereby prevent burning of a sheet which may accidentally come to rest over the flame.

sheet which may accidentally come to rest over the flame.

6. In a device of the character described, means for feeding electrically charged sheets to a sheet repository, a sheet repository located at the discharge end of the sheet feeding means to receive the sheets therefrom, flame producing means including a perforated pipe positioned between the sheet feeding means and the repository transversely of the path of the sheets, a flame shield movably mounted adjacent the pipe and adapted to be moved over the pipe to shield the sheets from the flame, a valve connected to the pipe for controlling the flow of gas to the pipe, and means for momentarily moving the shield over the pipe and operating the valve to diminish the flow of gas after a sheet has passed over the flame, to thereby prevent burning of a sheet which may accidentally come to rest over the flame.

7. In a device of the character described, means for feeding electrically charged sheets to a sheet repository, a sheet repository located at the discharge end of the sheet feeding means to receive the sheets therefrom, flame producing means including a perforated pipe positioned between the sheet feeding means and the repository transversely of the path of the sheets, a flame shield pivotally mounted across the path of the sheets in parallel relation to the pipe and adapted to be moved over the pipe, a valve connected to the pipe for controlling the flow of gas to the pipe, and means operable in timed relation with the sheet feeding means for simultaneously actuating the flame shield and the valve to momentarily render the flame ineffective after a sheet has passed over the flame, to thereby prevent burning of a sheet which may accidentally come to rest over the flame.

8. In a device of the character described, means for feeding electrically charged sheets to a sheet repository, a frame for supporting said sheet feeding means, a sheet repository located at the discharge end of said sheet feeding means, flame producing means including a perforated pipe mounted transversely of the frame between the sheet feeding means and the repository, a shaft journaled transversely of the frame adjacent the pipe, a flame shield fixed to said shaft and movable to a position over the pipe upon rotation of the shaft, and means operable in timed relation with the sheet feeding means for actuating the shaft to momentarily move the flame shield over the pipe to shield the flame from the path of the sheets after a sheet has passed over the flame, to thereby prevent burning of a sheet which may accidentally come to rest over the flame.

9. In a device of the character described, means for feeding electrically charged sheets to a sheet repository, a frame for supporting said sheet feeding means, a sheet repository located at the discharge end of said sheet feeding means, flame producing means including a perforated pipe mounted transversely of the frame between the sheet feeding means and the repository, a shaft journaled transversely of the frame adjacent the pipe, a flame shield fixed to said shaft and movable to a position over the pipe upon rotation of the shaft, a jogger shaft journaled on the frame in parallel relation to said shield shaft, and operating connections between said shafts for actuating the shield shaft upon rotation of the jogger shaft whereby the flame shield will momentarily move over the pipe and shield

the flame from the path of the sheet after a sheet has passed over the flame, to thereby prevent burning of a sheet which may accidentally come to rest over the flame.

10. In a device of the character described, means for feeding electrically charged sheets to a sheet repository, a frame for supporting said sheet feeding means, a sheet repository located at the discharge end of said sheet feeding means, flame producing means including a perforated pipe mounted transversely of the frame between the sheet feeding means and the repository, a shaft journalled transversely of the frame adjacent the pipe, a flame shield fixed to said shaft and movable to a position over the pipe upon rotation of the shaft, a jogger shaft journalled on the frame in parallel relation to said shield shaft, operating connections between said shafts for actuating the shield shaft upon rotation of the jogger shaft, a valve connected to the pipe for controlling the flow of gas to the pipe, and operating connections between the valve and jogger shaft whereby the valve will be operated to diminish the flow of gas to the pipe and the flame shield will move over the pipe, to thereby prevent burning of a sheet which may accidentally come to rest over the flame.

11. In a device of the character described,

means for feeding electrically charged sheets to a sheet repository, a frame for supporting said sheet feeding means, a sheet repository located at the discharge end of said sheet feeding means, flame producing means positioned between the sheet feeding means and the repository in the path of the sheets, and means located between the flame producing means and the repository and projecting above the latter for preventing accidental return of the sheets over the flame after they have been discharged into the repository.

12. In a device of the character described, means for feeding electrically charged sheets to a sheet repository, a frame for supporting said sheet feeding means, a sheet repository located at the discharge end of said sheet feeding means, flame producing means positioned between the sheet feeding means and the repository in the path of the sheets, and means located between the flame producing means and the repository for preventing accidental return of the sheets over the flame after they have been discharged into the repository, said means comprising a transversely extending guard having its upper end bent downwardly over the repository to form an overhanging sheet retaining lip.

GEORGE B. SAMMONS.
